UNITED STATES PATENT OFFICE

161,419

FRUIT JUICE DISPENSER

William F. Burger, Jacksonville, Fla., assignor to Orange State Dispenser Corporation, Jacksonville, Fla., a corporation of Florida

Application March 31, 1950, Serial No. 8,891

Term of patent 14 years

(Cl. D2—3)

To all whom it may concern:

Be it known that I, William F. Burger, a citizen of the United States and a resident of Jacksonville, in the county of Duval and State of Florida, have invented a new, original, and ornamental Design for a Fruit Juice Dispenser, of which the following is the specification, reference being had to the accompanying drawing forming a part thereof.

The other side is substantially like the side shown.

I claim:

The ornamental design for a fruit juice dispenser, substantially as shown and described.

WILLIAM F. BURGER.
